UNITED STATES PATENT OFFICE.

FRANK F. BURTON, OF MOUNT CARMEL, CONNECTICUT, ASSIGNOR TO WINCHESTER REPEATING ARMS CO., OF NEW HAVEN, CONNECTICUT, A CORPORATION.

EXTRACTOR FOR BREAKDOWN GUNS.

1,322,287.

Specification of Letters Patent. Patented Nov. 18, 1919.

Application filed August 16, 1919. Serial No. 318,009.

To all whom it may concern:

Be it known that I, FRANK F. BURTON, a citizen of the United States, residing at Mount Carmel, in the county of New Haven and State of Connecticut, have invented a new and useful Improvement in Extractors for Breakdown Guns; and I do hereby declare the following, when taken in connection with the accompanying drawings and the characters of reference marked thereon, to be a full, clear, and exact description of the same, and which said drawings constitute part of this application, and represent, in—

15 Figure 1 a broken view in side elevation of a break-down gun embodying my invention, the barrel and forearm being shown by broken lines in their broken down positions.

Fig. 2 an enlarged broken view in central vertical longitudinal section of the breech portion of the gun, a cartridge being shown in the chamber of the gun-barrel.

Fig. 3 a view of the gun in vertical transverse section on the line 3—3 of Fig. 2.

25 Fig. 4 a view corresponding to Fig. 2 with the gun shown as broken down or open, and the cartridge as partially extracted.

Fig. 5 a detached view in rear elevation of the forearm, showing the rocking extractor-actuator mounted therein.

Fig. 6 a detached broken view in side elevation of the forearm.

Fig. 7 an end view thereof with the extractor-actuator removed.

35 Fig. 8 a detached view in rear elevation of the gun-barrel.

Fig. 9 a detached broken view thereof in side elevation.

Fig. 10 a detached view in side elevation of the extractor.

Fig. 11 a front view thereof.

Fig. 12 a detached view in side elevation of the extractor-plunger.

Fig. 13 a front view thereof.

45 Fig. 14 a detached perspective view of the extractor-catch.

Fig. 15 a corresponding view of extractor-actuator.

50 Fig. 16 a plan view of the extractor-actuator staple.

My invention relates to an improved extractor for breakdown guns, the object being to provide simple and reliable means for positively operating the extractor in case 55 the cartridge sticks beyond the capacity of

the extractor-spring to extract it from the chamber of the gun-barrel.

With these ends in view, my invention consists in certain details of construction as will be hereinafter described and pointed out in the claims.

In carrying out my invention, as herein shown, I employ what I shall, for want of a more convenient term, call a rocking extractor-actuator which consists of a crescent-shaped plate 4 having its inner face formed with a retaining-notch 5 receiving the reach of a staple 6 by which the part is loosely held in place in a shallow vertical segmental slot 7 formed in the center of the shoe 8 mounted upon the rear end of the forearm 9 of the gun. As thus mounted the extractor-actuator has sliding, rocking movement in the staple 6, within the limits imposed by the length of its notch 5.

My improved extractor-actuator is positioned to engage at its upper end with the forward end of an extractor-plunger 10 projecting through the forward end of a long, axial bearing-hole 11 formed in a lug 12 depending from the breech end of the gun-barrel 13. The rear portion of the said plunger is encircled by a helical extractor-spring 14 the forward coil of which impinges upon a shoulder 15 formed by reducing the size of the hole 11 to the diameter of the plunger, while the rear coil of the said spring impinges upon the forward face of the plunger-head 16 the rear face of which engages with the forward end of the stem 17 of an upstanding extractor-head 18 which normally fits into a slot 19 in the rear end of the gun-barrel. The said plunger head 16 and stem 17 have a sliding fit in the hole aforesaid. The upper edge of the extractor-head 18 is shaped to engage with the rim 20 of a cartridge 21 when the same is fully inserted into the chamber of the gun-barrel 13 as shown in Fig. 2.

The extractor-stem 17 has its lower face cut away to produce a catch-shoulder 22 and a stop-shoulder 23 located toward its forward end and co-acting in sequence with the nose 24 of a pivotal extractor-catch 25 located within a vertical slot 26 in the lug 12 and hung upon a pivot-pin 27 passing through the same. At its rear end the catch is formed with an upstanding lug 28 entering a cut 29 in the lower face of the extractor-stem 17 and preventing the same 110

from rotating. At its forward end the catch 25 is formed with a round transverse hole 30 receiving an operating-pin 31 which moves up and down in a slightly circular path as the catch swings upon its pin 27, clearance being provided for this movement by holes 32 (Figs. 2, 3 and 4) in the side walls of the slot 26 in the lug 12 depending from the barrel 13. The projecting ends of the pin 31 enter clearance-recesses 33 formed in the inner faces of the side walls of the receiver 34 as best shown in Fig. 3. When the gun is broken down, as shown in Fig. 4, the upper faces of the projecting ends of the pin 31 engage with the upper walls 35 of the said recesses 33 with the effect of positively rocking the catch 25 upon its pivot-pin 27 against the tension of a helical catch-spring 36 located in a circular hole 37 formed to receive it in the lug 12 and leading out of the rear wall of the slot 26 formed therein for the reception of the catch 25. A heavy pin 38 mounted in the receiver and having its upper face cut away as at 39 to clear the plunger 10, fits into a semi-circular groove 40 in the front end of the lug 12 and provides a fulcrum upon which the barrel turns in breaking down the gun. To return now to the crescent-shaped extractor-actuator 4, its lower edge is engaged by the forward edge 41 of the floor 42 of the receiver 34.

As thus constructed and arranged, the rocking extractor-actuator 4 is interposed between the forward end of the receiver and the forward end of the extractor-plunger at a point in front of the fulcrum on which the barrel and the receiver turn, so that when the gun is broken down, the receiver positively rocks the actuator which slides in a circular path in the staple 6, so as to engage its upper end with the forward end of the plunger 10 and positively force the same from front to rear provided that the extractor-spring 14 did not move the plunger 10, and hence the extractor, rearward as soon, in the opening of the gun, as the engagement of the projecting ends of the pin 31 with the upper walls 35 of the recesses 33 operated the catch 25 to retract the nose 24 thereof from the catch-shoulder 22 of the extractor. When the gun is closed, the face 43 of the receiver 34 will engage with the curved lower corner of the rear face of the extractor-head 18 and force the same forward against the tension of the spring 14 which is in this manner placed under the compression required for the normal extraction and ejection of the spent cartridges. Just as the extractor nears the limit of its forward movement, its catch-shoulder 22 is

engaged by the nose 24 of the catch 25 acting under the influence of its spring 36. During this closing movement of the barrel and the forward movement of the extractor, the forward end of the plunger 10 engages with the upper end of the actuator 4 and rocks and slides the same back into its normal position in which it is shown in Fig. 2. It will thus be seen that when the gun is broken down, the actuator acts to positively operate the extractor in case the spring fails to operate the same automatically. It is expected, however, that in the ordinary operation of the gun, the spring will operate the extractor to extract the cartridge from the chamber, the actuator being provided only to insure the starting of the cartridges in case they stick. Normally the actuator operates, but operates idly.

I claim:

1. A break-down gun having a receiver, a forearm, a shoe mounted thereupon and formed with a vertical segmental slot, a barrel fulcrumed in the receiver, a cartridge-extractor, a crescent-shaped, rocking extractor-actuator located in the said segmental slot in position to be operated by the said receiver for positively pushing the said extractor rearward when the gun is broken down and formed upon its concaved inner face with a notch by means of which its sliding rocking movement is limited, and a staple mounted in the said shoe and embracing the said extractor-actuator for holding the same in the said slot and limiting its rocking movement.

2. A break-down gun having a receiver, a forearm, a shoe mounted thereupon and formed with a vertical segmental slot, a barrel fulcrumed in the receiver, a cartridge-extractor, a spring therefor, an extractor-plunger, an extractor-catch, a crescent-shaped, rocking extractor-actuator located in the said segmental slot in position to be operated by the said receiver for positively pushing the said plunger rearward when the gun is broken down and formed upon its concaved inner face with a notch by means of which its sliding rocking movement is limited, and a staple mounted in the said shoe and embracing the said extractor-actuator for holding the same in the said slot and limiting its rocking movement.

In testimony whereof, I have signed this specification in the presence of two subscribing witnesses.

FRANK F. BURTON.
